UNITED STATES PATENT OFFICE.

ANDREW CHRISTIANSON, OF BUTLER, PENNSYLVANIA.

DUST-GUARD FOR JOURNAL-BOXES.

1,178,133.

Specification of Letters Patent.

Patented Apr. 4, 1916.

Application filed April 25, 1913. Serial No. 763,547.

To all whom it may concern:

Be it known that I, ANDREW CHRISTIANSON, a citizen of the United States, and resident of Butler, in the county of Butler and State of Pennsylvania, have invented a new and useful Improvement in Dust-Guards for Journal-Boxes; and I do hereby declare the following to be a full, clear, and exact description thereof.

10 My invention relates to dust guards for journal boxes and is particularly, though not exclusively, designed for use in an M. C. B. box, which has a receptacle or chamber at the rear for the reception of dust excluding devices.

20 The object of the invention is to provide a device of this character which may be placed in position within this chamber or within the journal box and having means to hold it in proper position to receive the axle and to also hold it securely against the wall of the journal box around the journal opening to effectually exclude dust.

25 With these objects in view, the invention consists in a construction and arrangement of dust guard, a preferred embodiment of which is illustrated in the accompanying drawings in which—

30 Figure 1 is a view in vertical section of a journal box showing the dust guard in place therein, and the end of the axle in elevation; Fig. 2 is a face view of the dust guard; and Fig. 3 is a sectional view on the line 3—3 Fig. 2 of the guard.

35 Referring to Fig. 1 of the drawings, 1 indicates an ordinary M. C. B. journal box having at the rear the double walls 2, 3, forming a dust guard receiving chamber 4 at the point where the axle 5 enters the journal box. The dust guard proper may be of a variety of forms but in the construction here illustrated it comprises a body portion 6 of felt centrally apertured as at 7, Fig. 2, and having secured upon either face thereof 40 reinforcing linings 8 of canvas or like strong material. The canvas linings are secured to the felt body 6 by lines of stitches 9 around the outer edges of the dust guard and by a line of stitches 10 around the aperture 7 which receives the axle. These lines of stitches pass through the felt body as indicated at 9 and 10 in Fig. 3. The edges of the linings both at the periphery and around the aperture of the dust guard terminate just within the edges of the felt body as in- 45 dicated at 11 and 12 respectively, Figs. 2 and 3, so that the felt which is of looser texture than the canvas linings closely hugs the axle and spreads more or less thereon to effectually exclude the entrance of dust and 50 also the outside terminations of the guard may be such that the exposed outer edges thereof may snugly engage the side walls and bottom of the chamber 4 between the double walls 2, 3, thus effectually preventing 55 the entrance of dust around the edges of the guard.

A special feature of the invention, however, resides in the means for causing the dust guard to snugly engage the rear wall 70 of the chamber 4 at all points adjacent to the axle. This I accomplish by providing means such as a looped steel spring 13 which is secured at intervals to and through the canvas linings of the body of the dust guard 75 either by stitches or by suitable staples 14. This steel spring is of the form clearly indicated in Fig. 3 and comprises inturned loops 15 which are utilized to receive the fastening stitches or staples which thus hold 80 the spring against sliding or slipping on the body of the dust guard and the outturned loop portions 16 which form in effect a series of resilient springs around the axle-receiving opening of the guard which springs 85 are compressed more or less when the device is placed in the chamber 4 between the double walls 2, 3, and hold the opposite face of the dust guard firmly against the inside 90 of the rear wall 3, so that no dust may gain 95 access to the dust guard receiving chamber and thus work around into the journal box. Furthermore, these spring loops serve to hold the exposed raw edge of the felt at the axle and opening snugly against the axle or 100 rather prevent the axle from pushing this raw edge back or out of contact with the axle. These spring loops also serve to hold the dust guard in proper alinement with the axle receiving opening of the journal box so 105 that the axle may be readily inserted without damaging the dust guard. The double lines of stitching 9 and 10 also serve to swell or bulge the body of the dust guard between them and cause such bulged portions of the 110 dust guard more effectually to engage the walls of the dust guard chamber 4. Thus this canvas lining and lines of stitches serve the double purpose of maintaining the proper shape of the dust guard and also

shaping it to more effectually perform its functions as a dust excluder.

While I have herein described a particular embodiment of the invention, it is to be understood that it may be altered in details of construction and arrangement of parts within the scope of the appended claims.

What I claim is:—

1. A dust guard comprising a body portion of dust excluding material having a lining of shape retaining fabric secured thereto, said parts being apertured, the aperture being shaped to receive the axle or shaft and resilient means arranged around said aperture to maintain the face of said dust excluding material snugly against the wall of the journal bearing adjacent the axle.

2. A dust guard comprising a body portion of felt apertured to receive an axle or shaft, said body portion being lined upon either side with shape retaining fabric stitched to the body continuously around said aperture and around the outer edges of the body portion and a spring member extending continuously around said aperture adjacent the edge thereof to hold the dust guard securely against a wall of the journal bearing adjacent the shaft.

3. A dust guard comprising a body portion of felt apertured to receive a shaft or axle having lining layers of shape retaining fabrics secured to either face thereof, the edges of said lining layers adjacent said apertures terminating within the edges of the felt leaving the felt free to engage the axle or shaft and a spring member comprising a series of outwardly extending loops secured to said dust guard and extending continuously around the aperture therein to hold the axle engaging edges of the dust guard securely against an adjacent wall of the journal bearing and to maintain

the edge of the dust guard snugly in engagement with the axle or shaft.

4. A dust guard for journal boxes, comprising a body portion of dust excluding material apertured to receive an axle or shaft and an annular spring strip secured to one face of said body portion adjacent the aperture thereof to force said body portion against one wall of the journal box and to hold the material of the body portion in close engagement with the shaft or axle.

5. A dust guard for a journal bearing comprising a body portion of dust excluding material apertured to receive an axle or shaft, and a spring ring comprising a series of outwardly extending loops and intermediate inwardly extending loops, the latter being secured to said dust guard, said ring extending continuously around the aperture in the body portion to hold the axle engaging edges of the dust guard securely against an adjacent wall of the journal bearing and to maintain the edge of the dust guard snugly in engagement with the axle or shaft.

6. A dust guard for a journal bearing comprising a body portion of dust excluding material apertured to receive an axle or shaft, an annular resilient wire member secured to said body portion adjacent said aperture to hold the body portion against an adjacent wall of the journal bearing and to permit the portions of the body portion both within and without the ring to spread laterally whereby they may adequately fill the dust guard receiving socket in the bearing to exclude the dust therefrom.

In testimony whereof I the said ANDREW CHRISTIANSON, have hereunto set my hand.

ANDREW CHRISTIANSON.
